MEASURING BOWL

Filed March 31, 1922

Inventor
R.R. Johnson,

Attala Tech.

Attorney

UNITED STATES PATENT OFFICE.

RICHARD R. JOHNSON, OF GREAT FALLS, MONTANA.

MEASURING BOWL.

Application filed March 31, 1922. Serial No. 548,519.

To all whom it may concern:

Be it known that I, RICHARD R. JOHNSON, a citizen of the United States of America, and a resident of Great Falls, Cascade 5 County, Montana, have invented certain new and useful Improvements in Measuring Bowls, of which the following is a specification.

This invention relates to certain improvements in measuring bowls and the like; and the nature and objects of the invention will be readily understood by those skilled in the art in the light of the following explanation and detailed description of the accompanying drawings illustrating what I at present consider to be the preferred embodiments or mechanical expressions of my invention from among various other forms, arrangements combinations and constructions 15 within the spirit and scope thereof.

The invention pertains and is applicable generally to bowls and containers employed in the arts for measuring and mixing various materials, and ingredients, as well as for other purposes, but is particularly directed and applicable to the types of bowls used in dentistry for mixing so-called investment materials. In the practice of dentistry it is necessary to prepare various "mixes" from 25 investment materials for use in carrying out certain dental work. At the present time flexible rubber bowls are in practically universal use by dentists for mixing investment materials and for similar purposes, as well 30 known to those familiar with the practice of dentistry. These rubber mixing bowls are formed of a degree of flexibility to permit of their being flexed or compressed to break up and remove any materials or mix which 35 has become hardened therein, yet the bowls 40 have sufficient stiffness or rigidity to normally retain their proper shape and form as bowls.

In the usual method followed in preparing a mix in one of these rubber bowls, water, for example, is first poured into the bowl in what is estimated to be the necessary quantity to properly prepare the desired amount and character of mix, then the 45 plaster or other investment materials to be used are placed into the bowl in what is estimated to be the proper quantity, and the contents of the bowl are then stirred with a spatula or other suitable instrument, until 50 the materials are properly mixed. Now, with

the use of mixing bowls of the type referred to, the quantities and amounts of the materials placed therein to prepare a desired mix are necessarily roughly estimated or guessed at, as there are no guides or indications by which the user can gauge or measure the quantities of the material being placed or poured into a bowl. Experience has shown that the usual tendency in placing materials in a bowl to prepare a mix is to 60 over estimate the amount or quantity of the material, so that the resulting mix is usually more than required and waste results.

With the use of the expensive investment materials essential in cast metal inlay work, 65 it is readily seen that the waste resulting from preparing excessive quantities of a mix will in the aggregate amount to a considerable loss and expense. Further, the preparation of mixes with the referred to 70 type of bowl by the foregoing method dependent upon rough estimation and guess, results in a lack of uniformity in the mixes so prepared and a natural decrease in the 75 quality and character of the work utilizing 80 and based upon such mixes. It follows from the foregoing specific mixing bowl problem encountered in the practice of dentistry, that in other arts and with the use generally of 85 bowls for mixing purposes this problem 90 is present where it is necessary to place materials in a bowl without any guide or indication by which the quantities and amounts 95 can be measured.

Therefore, one of the main objects of the 90 present invention is to provide a mixing bowl or container so constructed and arranged as to overcome the aforementioned problems by forming the bowl with permanent markings and indications incorporated in and 95 forming a part of the body of the bowl to provide graduations by which the quantities of material placed can be readily and rapidly 100 gauged or measured.

A further object of the invention is to 100 provide a measuring bowl formed of elements having different appeals to the eye, so arranged and combined in assembled bowl forming relation as to provide a series of 105 permanent indications or graduations in the bowl by means of which material can be measured therein to the required quantity.

A further object of the invention is to 110 provide a flexible rubber or analogous material bowl, formed from superposed rings

and bands of differently colored material arranged in contrasting colored relationship in the bowl to provide a series of permanent graduations within the bowl by means of which a user can readily measure or gauge the quantity of material placed into the bowl; and to provide a bowl so formed in which the desired flexible characteristic is retained without detracting from the durability or life of the bowl, or from the permanency of the graduations formed therein.

A further object of the invention is to provide a mixing and measuring bowl having a series of circumferential graduations around the inner surface of the bowl and incorporated in and forming a part of the body of the bowl, so that in using the bowl these graduations provide a gauge by means of which the quantity of material placed therein can be measured to that required for the particular purpose for which the material is intended.

A further object of the invention is to provide a method of forming flexible rubber measuring bowls from a series of rings and bands of differently colored rubber to obtain a series of permanent indications or graduations in and forming a part of the body of the bowl.

With the foregoing and various other objects in view, which will be readily recognized and appreciated by those skilled in the arts involved, the invention consists in certain novel features in constructions and in arrangements and combinations of elements, as more fully and particularly set forth and specified hereinafter.

Referring to the accompanying drawings:

Fig. 1 is a perspective view of a measuring bowl formed in accordance with the present invention.

Fig. 2 is a vertical transverse section through a measuring bowl of the form and construction of Fig. 1.

Fig. 3 is a view in vertical section of the elements of a bowl of the form of Fig. 1, the elements being shown in their proper relative positions for assembly and formation into a bowl by the method of the invention.

Fig. 4 is a vertical section through another form of bowl embodying the invention.

Figs. 5 and 6, are vertical sections of other forms of bowls embodying the invention.

In the accompanying drawings, I have illustrated the invention as applied to and forming measuring bowls of the flexible rubber type employed by dentists for mixing investment materials, due to the fact that the problems solved by the invention are encountered in an exaggerated form in such types and material of bowl and serve to more clearly illustrate and bring forth the invention and the problems overcome

thereby. However, it is not intended to limit the invention to the types of bowl illustrated and described herewith purely by way of example, as it will be readily apparent to those skilled in the art that the invention is applicable to mixing bowls and containers generally where it is desirable to measure the materials placed therein.

One form and embodiment of a flexible rubber measuring bowl embodying the features of and constructed in accordance with the invention, is illustrated in Figs. 1, 2 and 3 of the drawings. In this form the bowl A, comprises a base 10 and a series of superposed bands or rings 11, 12 and 13. The base 10 and bands 11, 12 and 13 are formed of different and contrastingly colored rubber so that in effect circumferential lines forming indications or graduations 14, 15 and 16 are provided around the inner surface of the bowl between the adjacent abutting and joined edges of the contrastingly colored base and bands of which the bowl A is formed. In the illustrated example, the base 10 and bands 11, 12 and 13 are formed from rubber of two colors and are arranged in alternate relation to form the bowl, that is a band of one color of rubber is superposed upon and joined to a band of the other color rubber and this is carried out so that the bands forming the bowl are alternately of different and contrasting color to the color of the bands respectively adjacent and joined thereto. In the present instance, red and black rubber are used, rubber of these two colors being common and in universal commercial use as well known in this art, and the bowl base 10 is formed of black rubber, the band 11 superposed on and joining the base 10 is formed of red rubber, the next band 12 is black rubber, and the top or upper band 13 is of red rubber. Thus, the arrangement of alternately joining black and red bands of rubber to form the bowl A, provides the inner circumferential indications or graduations 14, 15 and 16 at different levels or depths within the bowl at the abutting and joined edges of the contrastingly colored bands.

In this manner the bowl A is formed with permanent graduations incorporated in and forming a part of the body of the bowl by means of which the quantity of material placed therein can be gauged.

A flexible rubber measuring bowl of the type above described, can be formed by preparing the base 10 and bands 11, 12 and 13 of the desired different colored unvulcanized rubber, then assembling the base and bands in proper bowl forming and contrastingly colored relation, as shown in Fig. 3 of the drawings. The shape of the bowl can be formed as desired by the diameter and curvature given the base and bands of which

the bowl is to be constructed, as will be readily apparent. After the base and bands are in proper relation they are superposed with the adjacent edges abutting and placed in a suitable vulcanizing form or mold and there vulcanized together to provide the integral, one-piece bowl body in which the graduations 14, 15 and 16 are permanently incorporated in and form a part of the bowl body.

Another form of the invention is illustrated in Fig. 4, in which the base 10, and the bowl forming bands 11, 12 and 13 are formed of one color of rubber and have the thin flat rings 17, 18 and 19 interposed therebetween, respectively.

The rings 17, 18 and 19 are of a width equal to the thickness of the bowls with their inner peripheral edges flush with the inner surface of the bowl and forming circumferential graduations or lines around the inner surface of the bowl. In this form of the invention the bowl B is formed by vulcanizing the bands and graduation rings together, so that the rings form and become an integral permanent part of the body of the bowl. An effective color scheme for the bowl B is to form the base 10, and bands 11, 12 and 13 of black rubber, and the graduation rings 17, 18 and 19 of white rubber, as shown in the drawings, so that the black rubber of the base and bands provides a background for the white rubber rings.

In Fig. 5 of the drawings, another form and embodiment of which the invention is capable is illustrated. In this form a bowl C is composed of a one-piece flexible rubber body 20, which is provided with circumferential grooves in the inner surface of the bowl body 20 at different depths or levels therein, and the ring or the like inserts 21, 22 and 23 are placed in the grooves and vulcanized therein to form the graduations or lines integral with and forming a permanent part of the bowl body. In the illustrated example of this form of the invention, the bowl body 20 is formed of black rubber and the rings or graduation forming inserts 21, 22 and 23 are formed of which white rubber, as clearly indicated in Fig. 5.

The form of measuring bowl D embodying the invention and illustrated in Fig. 6 of the drawings, comprises the one piece bowl forming body 24 in which graduation lines 25, 26 and 27 are formed around the inner surface of the bowl at different levels therein. In this form of bowl the lines 25, 26 and 27 may be placed on the inner surface of the bowl by suitably discoloring the material of which the bowl is formed, or where molded or the like from plastic material the graduations lines may be formed thereon in the process of forming the bowl.

As illustrated, the bowl body is formed of

black material and the graduations are formed thereon as a white color to clearly stand out against the block of the inner surface of the bowl body.

Where the invention is embodied in and provides a flexible rubber bowl of the type employed in dentistry for mixing investment and the like materials, the graduations formed in the bowl provide a means by which the materials to prepare a mix can be measured therein to insure the necessary amounts for the required mix without waste of material through rough estimation or guess as to the quantities of the material placed therein. In each instance, the user will know the required amounts which should be placed in the bowl and the particular graduation formed in the bowl by which each amount is determined or measured, so that it merely becomes necessary to place the materials in the bowl to the proper graduations to prepare the required mix. It is thus clear, that by the use of the graduated bowls of the invention, the expensive waste of investment and like materials, referred to hereinbefore, is overcome and a uniformity and standardization of the mixes prepared results. Further, the flexible bowls embodying the invention retain the required flexibility but without impairing or detracting from the permanency of the graduations by breaking, cracking or in wear and use of a bowl, as the graduations are incorporated in and form an integral part of the body of the bowl and have a life and effectiveness equal to the life of the bowl.

The various features of the invention can be applied generally to mixing bowls, containers and graduates employed in the arts and are not limited to the flexible rubber type, as they are equally applicable to other types and materials, particularly in bowls or containers subject to the action of great wear and of corrosive action of the materials used therein. The number and arrangement of the bands and rings forming the graduations is not limited to the illustrated bowls, nor are the colors illustrated an essential feature of the invention, as any number, arrangement or colors may be utilized without stepping beyond the limits of the invention. If desired the contrasting colors may not be employed, but instead the graduations may be formed by bands or rings having differently formed surfaces to provide the desired contrast and appeal to the eye to define the measuring lines or graduations.

It is evident that variations, changes and modifications can be resorted to without departing from the spirit and scope of the invention defined by the following claims, hence I do not wish to limit my invention to the exact disclosure hereof.

Desiring to protect my invention in the

broadest manner legally possible, what I claim is:

1. A measuring bowl including a series of superposed rings of contrasting colors joined together to form the bowl, the joined edges of said contrastingly colored rings forming a series of graduations within the bowl.
2. A flexible measuring bowl provided 10 with graduations formed by separate elements incorporated in and forming an integral part of the body of the bowl.
3. A measuring bowl including a series 15 of rings of contrasting colors, the said rings superposed in registration with their adjacent edges abutting and joined together to form a substantially integral one-piece bowl structure.
4. A flexible measuring bowl including a 20 series of rings superposed in alinement with their edges abutting and joined together, the joined edges of said rings providing a series of circumferential graduations around the inner surface of the bowl.
- 25 5. A flexible rubber mixing bowl including a series of contrastingly colored rubber

rings superposed with their adjacent abutting edges secured together to form a one-piece bowl, the said contrastingly colored rubber rings forming a series of circumferential graduations therebetween around the inner surface of the bowl.

30 6. A flexible rubber measuring bowl formed of a base, and a series of rubber rings superposed thereon and having their adjacent abutting edges vulcanized together to provide a one-piece bowl, the said rings contrastingly colored whereby the bowl is divided into a series of depths indicated at the merging of the color of the rings with the colors of the rings adjacent thereto, respectively.

35 7. In a measuring bowl, a series of ring-like elements having different visual appeals, the said elements superposed in registration and joined together to form substantially integral one-piece bowl walls, and the said elements of different visual appeals so joined forming a series of graduations in and on the bowl walls.

RICHARD R. JOHNSON.
